United States Patent Office

Des. 193,425
Patented Aug. 21, 1962

193,425

AUTOMOBILE

Hugh W. Shumaker, 517 S. Jackson St., Moscow, Idaho

Filed Jan. 26, 1961, Ser. No. 63,714

Term of patent 14 years

(Cl. D14—6)

Fig. 1.

FIG. 1 is a side elevation view of an automobile showing my new design;

FIG. 2 is a rear perspective view thereof;

FIG. 3 is a front perspective view thereof;

FIG. 4 is a fragmentary side elevation view thereof.

The dominant features of my design reside in the portion shown in full line. Portions of the automobile are omitted in FIGS. 2, 3 and 4 for convenience of illustration. The side not shown is a mirror image of the side shown.

I claim:

The ornamental design for an automobile, substantially as shown and described,
